UNITED STATES PATENT OFFICE

EMILE GIRARDEAU, OF PARIS, FRANCE, ASSIGNOR OF ONE-HALF TO JOSEPH BETHENOD, OF PARIS, FRANCE.

AUTOMATIC COMMUTATOR FOR RADIOTELEGRAPHIC PLANTS WITH INDIRECT EXCITATION.

1,105,029.

Specification of Letters Patent. Patented July 28, 1914.

Application filed December 4, 1911. Serial No. 663,772.

To all whom it may concern:

Be it known that I, EMILE GIRARDEAU, citizen of the French Republic, residing at Paris, Republic of France, have invented 5 certain new and useful Improvements in Automatic Commutators for Radiotelegraphic Plants with Indirect Excitation, of which the following is a specification.

This invention relates to radiotelegraphic 10 plants with indirect excitation.

The invention has for its object a device which automatically makes the plant ready as a receiver as soon as the lever of the key is released. Thus a great rapidity is realized with regard to the exchange of the telegrams, the rapidity being almost the same as with ordinary Morse telegraphs.

Owing to this invention the operators can 20 interrupt the connection in case the receiver does not work properly, or if there is any error in the transmission or for any other reason.

In the accompanying drawings the invention is shown applied to a plant with 25 indirect excitation by direct coupling.

A is the antenna and P is the oscillatory sender circuit. According to this invention there is inserted at C, at a point which is as close as possible to the earth contact, an 30 interrupter, the contacts 1 and 2 of which are maintained separate by means of a spring 3 acting upon the movable contact 1. At the terminals of this interrupter, which has a very limited course only, (less than one millimeter), the primary circuit of the receiver jigger J is branched off, the receiver being of any of the well known types. The contact between the contacts 1 and 2 is produced by the excitation of the solenoid or electro- 35 magnet E₁ supplied with current from a suitable source B through the intermediary of a rheostat R. Under these conditions, when E₁ is at rest, there exists between the contacts 1 and 2 a small interval which is sufficient to stop the direct passage of the waves collected by the antennae, said electric waves being thus forced to pass through the primary winding of the jigger and consequently to actuate the detector D. If however the transmitting key M adapted for example to act (by means of a device not represented as not essential) upon the current of the source, is depressed, it closes an auxil- 40 iary contact (not represented) which makes the electromagnet E₁ ready to operate; and 55 the contacts 1 and 2 come at once in contact with each other, the primary winding of the jigger J being short-circuited, which generally, in a plant of medium size, is sufficient to insure the protection of the receiver devices. It has already been proposed to use for the last auxiliary contact a spring or equivalent device, in order to permit further the closing of the sender contact by means of the same key M. The adjustment of these two contacts must therefore be made with a great precision and obliges to use very complicated keys. According to the present invention, in order to avoid this great difficulty, the solenoid or 60 electromagnet E₁ is supplied by a suitable source B through the intermediary of a rheostat R, and when the key M is at rest, its 65 rocker, being in contact with the stop bar 5, short-circuits the winding of E₁, which is 70 thus rendered inoperative. The closing of the interrupter C is effected when the electromagnet E₁ ceases to be short-circuited, 75 namely as soon as the contact 4, 5 is opened. This last contact does not necessitate any 80 spring, as 5 is the stop bar of the key, and the operation is certainly good, whatever the course of the key M may be, which is no more complicated than an ordinary Morse key. The rheostat R serves to prevent the short 85 circuiting of the source B of energy when the key is at rest and it further reduces the time-constant of the circuit B, R, E₁ and thus improves the working conditions.

With very powerful plants, such as shown 90 in the drawings, the safety device hereinbefore described can be completed by disposing in the secondary jigger circuit a commutator I, the rocker 6 of which is pushed against the terminal 8 through the action of the 95 spring 9 so that the said commutator I closes the secondary circuit comprising the detector D, the apparatus being thus ready for reception. As soon however as the rocker 4 of the key M goes away from the stop 100 bar 5, a solenoid E₂ connected in series with E₁, pulls the rocker 6 away from the terminal 8 and brings the same in contact with the terminal 7. Under these conditions there is not only the secondary circuit interrupted 105 during emission but the secondary winding

of the jigger J is short-circuited upon itself, the detector D being thus protected in the very best manner.

One of the advantages of the installation shown in the drawings is that owing to the very short course of the interrupter C and of the commutator I, the electrodes 1 and 2 on the one hand and 7 and 8 on the other hand serve in any case as lightning-arresters for limiting the tension, protecting thus the receiver apparatus in case the circuit B, E₁, E₂, R should accidentally not work properly.

I claim:—

1. In an apparatus for wireless telegraphy the combination of a sender with a circuit comprising a pile or battery, a resistance, and an electro-magnet the armature of which is mounted on an oscillating lever which forms one of the contacts of an interrupter placed between the antenna and the earth and with a second circuit one of the ends of which is branched off between the electro-magnet and the battery, its second end being branched off between the electro-magnet and the resistance, this second circuit comprising an interrupter the movable part of which consists of the sender and opens the said second circuit if the said sender is being depressed.
2. In a receiver for wireless telegraphy an electro-magnet automatically excited by the sending of a signal, a commutator whose spring influenced arm is attracted by the electro-magnet at the moment when a signal is sent, a first circuit of which one end is electrically connected with the arm of the commutator, said circuit comprising the secondary winding of the jigger and a con-

ductor without lumped self induction or capacity which is connected with the contact 40 of the commutator on which the arm of the commutator is pressed when the electro-magnet is excited, said contact forming thus the second end of said first circuit; a second circuit one end of which is placed between 45 the secondary winding of the jigger and the said conductor and the other end of which is on the contact against which bears the arm of the commutator through the action of the spring when the electro-magnet is not 50 excited, this second circuit comprising the detector and a condenser.

3. In an apparatus for wireless telegraphy the combination of a sender with a circuit comprising a pile or battery, a resistance, a protecting commutator of the receiving circuit, a first electro-magnet which, when it is excited operates the protecting commutator of the receiving circuit, and a second electro-magnet the armature of which, when excited, grounds 60 the antenna, and with a second circuit one end of which is branched between the electro-magnets and the battery, its second end being branched off between the electro-magnets and the resistance, this second circuit 65 comprising an interrupter the movable part of which consists of the sender and opens the said second circuit when said sender is being depressed.

In witness whereof I have hereunto set 70 my hand in the presence of two witnesses.

EMILE GIRARDEAU.
